UNITED STATES PATENT OFFICE.

WILLIAM D. SHAFFER, OF SANTA PAULA, CALIFORNIA.

ROPE SOCKET.

Application filed March 14, 1921. Serial No. 452,063.

To all whom it may concern:

Be it known that I, WILLIAM D. SHAFFER, a citizen of the United States, residing at Santa Paula, in the county of Ventura, 5 State of California, have invented new and useful Improvements in Rope Sockets, of which the following is a specification.

In an application for patent entitled "Rope sockets" filed by me in the United 10 States Patent Office September 13, 1920, bearing Serial Number 409,754, I have shown and described a means for securing a rope socket to a wire cable end, which may be quickly and conveniently detached 15 therefrom when desired. In this construction a plurality of cone slips which are exteriorly conical in formation, are employed, and are adapted to be clamped around the cable end by being forced into a conical 20 bore in one of the socket members. This construction is in every respect satisfactory when a coreless steel cable is employed.

Generally in the drilling of oil wells, 25 steel cables having a soft hemp core are employed and the strain tending to pull the cable through the cone slips is very great.

The object of my present invention is to increase the holding power of the cone slips on the cable by removing from that part of 30 the cable end which is grasped between the cone slips, the core, and inserting in its place a non-pliable core of steel or other suitable material, thereby insuring a firmer grip on the cable.

35 Other objects of my invention will be disclosed in the following description, will be pointed out in the claims, and will be embodied in the accompanying drawings, in which:

40 Fig. 1 is a vertical section through a rope socket illustrating my invention as applied thereto.

Fig. 2 is a transverse section taken on the line 2—2 of Fig. 1.

45 In carrying out my invention the cable 10 is first prepared by removing a portion of the soft core 11 from its end and inserting in its place a hard core 12 composed of steel or other suitable material, said core 12 be- 50 ing preferably of a slightly greater diameter than the core 11 and tapered outwardly toward its free end as at 13. The outwardly extending end of the core 12 is preferably rounded as at 14 and the frayed 55 ends of the cable are preferably closed around said rounded end and twisted or

bound together as at 15, in order that said core will be effectively held in place in the cable end.

The elements comprising the rope socket 60 are of substantially the same construction, and perform the same function as those recited in my above mentioned application for patent, and consist of the socket body 16 which is provided with the centrally dis- 65 posed tapering bore 17, the contracted end of which communicates with the bore 18 through which the cable passes. A threaded bore 19 located at the lower end of socket body 16 is adapted to receive the threaded 70 end 20 of the subjunct member 21 and said end is provided with a depression 22 into which the end of the cable is adapted to project when all of the members are as- 75 sembled.

In assembling the various elements the cable end may be passed downwardly through bore 18 of member 16 below the lower end of the same, the cone slip mem- 80 bers 23 are then placed around said cable end and inserted into the conical socket 17. The semicircular inner surface of the lower ends of the cone slips 23 are flared outwardly and downwardly as shown at 24 in order to accommodate the flared lower 85 end of the cable end, and the adjusting washers or plates 25 are provided with apertures 26 through which the cable end may pass.

After the cone slips 23 have been inserted 90 into the bore 17 the subjunct 21 is screwed up into the threaded bore 19 which causes the cone slips to become wedged into bore 17 and thereby firmly clamp the cable end, and as said cable end has been reinforced 95 by the solid core member 12 it cannot be compressed out of shape and consequently the cone slips are caused to firmly grip said cable end.

As an additional safeguard against the 100 cable end slipping through the cone slips the tapered enlargement is provided on said cable end and core member 13.

What I claim is:

1. A rope construction, comprising a steel 105 cable having a flexible core extending a portion of its length, and a hard non-compressible core mounted therein and extending the remaining portion of its length, whereby to provide a cable having flexibility and non-compressibility.

2. A rope construction, comprising a steel

cable provided with a core, a portion of said core being flexible and the remaining portion being non-compressible, the non-compressible portion being located at one end 5 of said cable, whereby to attain flexibility in the major portion of the cable and non-compressibility in the minor portion thereof.

3. A rope construction, comprising a steel 10 cable provided with a core, a portion of said core being flexible and the remaining portion being non-compressible, the non-com-

pressible portion being located at one end of said cable, the extreme outer end of the non-compressible core being enlarged, 15 whereby to expand the extreme end of the cable.

In witness that I claim the foregoing I have hereunto subscribed my name this 28th day of February, 1921.

WILLIAM D. SHAFFER.

Witnesses:

EDNA SHAFFER,
ELIZABETH UNDERWOOD.
